UNITED STATES PATENT OFFICE.

EDWARD M. GRAHAM, OF CHICAGO, ILLINOIS.

PLIERS.

1,373,555.

Specification of Letters Patent.

Patented Apr. 5, 1921.

Application filed August 8, 1919. Serial No. 316,010.

To all whom it may concern:

Be it known that I, EDWARD M. GRAHAM, a citizen of the United States, and a resident of Chicago, in the county of Cook and State 5 of Illinois, have invented certain new and useful Improvements in Pliers, of which the following is a full, clear, and exact description.

The invention relates to pliers and its object is to provide improved cutting devices 10 on pliers.

It has been common practice heretofore to form integral cutting edges at one side of a pair of pliers. These have been found 15 to be objectionable, because the metal of the cutters was not suitably tempered to be efficient in cutting. One object of the present invention is to provide pliers with separately formed cutter-blades which are removably 20 secured to the jaws.

Another object of the invention is to provide improved cutter-blades for pliers which are adapted to be secured to the jaws by screws and in such manner that the screws 25 are not subjected to any severe stresses when metal is being cut.

A still further object of the invention is to provide pliers with reversible knives which are secured to the jaws.

30 The invention consists in the several novel features hereinafter set forth and more particularly defined by claims at the conclusion hereof.

In the drawings: Figure 1 is a side elevation of pliers embodying the invention. Fig. 2 is an end elevation. Fig. 3 is a section taken on line 3—3 of Fig. 1. Fig. 4 is a perspective of one of the cutters. Fig. 5 is a detail of one of the plier-jaws showing 40 the blade-retaining recess.

The invention is illustrated as applied to a device comprising two members pivotally connected by a pin 7, each having a jaw 8 and a handle 9, as well understood in the art.

45 One side of each jaw is formed with a recess 10 having V-shaped ends 11. Flat blades 12 are each provided with beveled cutting edges 13 and 14 on opposite edges thereof and with ends 15 which are V-shaped to conform to 50 the edges of the recess 10 in the jaws. Each blade 12 is removably secured to one of the jaws by a screw 16 which passes through a countersunk opening in the cutter and is screw-threaded to a hole in the jaw. The 55 blades are reversible in the recesses so that

either of their cutting edges can be rendered operative.

A characteristic of the construction set forth is that the blades are separately formed from the pliers and may be properly 60 tempered to render them efficient in cutting before they are secured to the jaws. Another characteristic is that when the cutters are operated, the outward stresses to which they are subjected as they are forced into the 65 metal being cut, is resisted by the outwardly convergent engaging edges between the blades and the jaws and, therefore, the screw is relieved of shearing or other stresses incident to cutting. Another characteristic is 70 that the blades are reversible so that when one edge becomes worn or broken a new cutting edge may be provided by simply reversing the blade in its retaining recess.

The invention is not to be understood as 75 restricted to the details set forth, since these may be modified within the scope of the appended claims, without departing from the spirit and scope of the invention.

Having thus described the invention, what 80 I claim as new and desire to secure by Letters Patent, is:

1. In pliers, the combination of a pair of pivotally connected members each having a gripping jaw, a handle and a recess extending in the plane of one of its outer side faces, substantially flat cutter blades removably secured and disposed in said recesses, the edges of said recesses and blades being conformably and outwardly convergent so that 90 the edges of the recesses will act as shoulders to resist the outward stresses upon the blades and being formed to permit the blades to be removed transversely from or placed transversely into the recesses while 95 the members are in connected relation, and means for removably securing the blades in the recesses.

2. In pliers, the combination of a pair of pivotally connected members, each having a gripping jaw, a handle and a recess extending in the plane of one of its outer side faces, substantially flat cutting blades fitting in said recesses, and screws extending directly through said blades and crosswise of the 105 jaws and removably securing the blades in the recesses, the edges of said recesses and blades being conformably and outwardly convergent so that the edges of the recesses will act as shoulders to resist the outward 110

stresses upon the blades and being formed to permit the blades to be removed transversely from or placed transversely into the recesses while the members are in connected relation.

3. In pliers, the combination of a pair of pivotally connected members, each having a jaw, a handle and a recess and extending in the plane of one of its outer side faces and substantially flat blades having a plurality of substantially parallel cutting edges, and means to removably secure the blades in the recesses, the blades being reversible so that either of the cutting edges may be brought into operative position, the blades being

transversely removable from and insertible in the recesses.

4. In pliers, the combination of a pair of pivotally connected members, each having a jaw with a recess in and extending in the plane of one of its outer side faces, and a handle, reversible substantially flat cutting blades fitting in said recesses, and means for removably securing the blades in the recesses, the edges of the blades and recesses being provided with substantially V-shaped interfitting edges formed to permit transverse removal or insertion of the blades while the jaws are in connected relation.

EDWARD M. GRAHAM.
